HENRY D. JAMES, OF EDGEWOOD, PENNSYLVANIA, ASSIGNOR TO WESTINGHOUSE ELECTRIC & MANUFACTURING COMPANY, A CORPORATION OF PENNSYLVANIA

ELEVATOR SAFETY SYSTEM

Application filed December 27, 1930. Serial No. 505,086.

My invention relates to multiple-car elevator systems and, more specifically, has relation to elevator systems whereby a plurality of elevator cars may be safely operated in a single hatchway.

A great saving of building space is accomplished by operating a plurality of cars in a single hatchway. The practical height of buildings is limited by the floor space taken up by the elevator hatchways necessary to provide elevator service. As the height of buildings is increased, the space devoted to elevator hatchways makes a greater encroachment upon the floor space, and a limiting condition is reached wherein the floor space available for productive purposes is no longer sufficient to yield an income commensurate with the increased cost of the building.

By operating more than one car in a hatchway, it is possible to increase the elevator service without making further encroachments upon the useful floor space. This arrangement is especially practical in high buildings having express-elevator service to the upper floors and local service to the lower floors, since an express car may be positioned and operated in the hatchway above each local car.

It is, accordingly, an object of my invention to provide a multiple elevator system wherein a plurality of elevator cars may be safely operated in a single hatchway.

It is also an object of my invention to provide a safety system for multiple elevators which will automatically maintain a predetermined minimum-space distance between the cars as they travel up and down the hatchway.

It is a further object of my invention to provide a multiple elevator system wherein the hoist motor of a car will be deenergized and its brake applied when it approaches another car in the hatchway, and wherein the safety device of the approaching car will be applied if it thereafter continues to approach the other car.

According to my invention, I utilize the governor rope of each car to successively open the control circuit and apply the safety device of the other car if the latter approaches

nearer than a certain predetermined distance.

The invention itself, however, both as to its organization and its method of operation, together with additional objects and advantages thereof, will best be understood from the following description of a specific embodiment, when read in connection with the accompanying drawings, in which:

Figure 1 is a diagrammatic view representing a dual elevator system arranged in accordance with my invention;

Fig. 2 is a plan view showing a pair of pivoted contact-controlling jaws represented diagrammatically at A, A' in the system shown in Fig. 1;

Fig. 3 is a view, in side elevation, of the pivoted jaws shown in Fig. 2;

Fig. 4 is a sectional view, taken on line IV—IV of Fig. 5, showing a pair of electromagnetically movable jaws represented at B and B' in the system shown in Fig. 1; and

Fig. 5 is a sectional plan view, taken on line V—V of Fig. 4.

Referring more specifically to the drawings, the apparatus shown in Fig. 1 comprises an elevator car C which is suspended by a hoisting cable Ca that passes over a hoisting drum D, in the usual manner. The hoisting drum D is directly coupled to the armature EM' of a hoisting motor EM.

A variable-voltage system of control may be provided for operating the elevator hoist motor EM wherein the armature EM' of the elevator motor is connected in a loop circuit 11, 12 with the armature G' of a generator G. The generator G is provided with a separately excited field winding GF and a cumulative series field winding GSF.

The armature G' of the generator G is driven by means of a driving motor M, having its armature M' and its field winding MF connected, in shunt relation, to a source of power designated as the supply conductors L1 and L2. The elevator motor EM has its field winding EMF connected, for constant-voltage energization, to the supply conductors L1 and L2.

In such system, the direction and speed of rotation of the elevator hoist motor EM is controlled by controlling the direction and

value of the excitation current that is supplied to the separately-excited field winding GF of the generator G. The direction of the excitation current for the field winding GF is controlled by means of an "up"-direction relay UR and a "down"-direction relay DR, while the magnitude of the current supplied to the field winding may be controlled by means of an intermediate-speed relay IR and a high-speed relay HR.

The operation of the relays UR, DR, IR and HR may be controlled by means of the car switch 'Cs that is mounted upon the elevator car C in position to be actuated by an attendant on the car. My safety system may, however, be utilized in conjunction with various types of elevator-control systems other than that specifically disclosed.

Mounted on the hoisting-machine shaft is a brake drum 13 which is engaged by a spring pressed brake shoe 14 to stop and hold the car. An electromagnet is provided comprising a winding 15 which is energized to withdraw the spring pressed brake shoe 14 and release the brake whenever the hoist motor EM is operating.

A governor, or safety-actuating rope 17 passes over a governor sheave 18 at the top of the hatchway and under a weighted and latched idler sheave 19 at the bottom of the hatchway. The rope 17 carries a "minnie ball" 21 which is releasably received by a spring clip 22 on the car C, whereby it is constrained to follow the car in its movements up and down the hatchway. An overspeed governor 23 is driven by the sheave 18 and is connected to a pair of rope-gripping jaws 24 which are thereby actuated to rope-gripping position when the car overspeeds. The car carries a safety device S of the conventional type which is actuated to grip the guide rails and stop the car by unreeling a safety cable 25 from the safety drum. The safety cable 25 passes around a guide pulley 26 and is attached to the governor rope 17.

If the car C overspeeds in the downward direction, the governor 23 actuates the rope-gripping jaws 24 to grip and lock the governor rope 17. The continued downward motion of the car C then causes the safety cable 25 to be unreeled from the safety drum which applies the safety S and stops the car C in the usual manner. The operation of the governor rope, the overspeed governor and the safety device is similar to the operation of corresponding elements provided in any conventional elevator system to prevent the car overspeeding from any cause, such as broken hoist cables or a defective control system.

Suspended in the same hatchway below the elevator car C, is a second car C' which is controlled by a hoist motor and control system identical with that shown for car C. The control system for car C' is not shown,

since it is identical with that shown in connection with car C and its illustration would unnecessarily encumber the drawings.

A governor rope 31 for car C' passes over a governor sheave 32 at the top of the hatchway and under a weighted idler sheave 33 at the bottom of the hatchway. The rope 31 carries a "minnie ball" 34 which is releasably received by a spring clip 35 on the car C', whereby the rope is constrained to follow the car C' in its movements up and down the hatchway. An overspeed governor 36 is driven by the sheave 32 to actuate a pair of rope-gripping jaws 37 in the conventional manner, as set forth with reference to car C and its associated apparatus. The safety device S', mounted on car C', is likewise of the conventional type which is actuated to grip the guide rails and stop the car to prevent overspeeding when a safety cable is unreeled from the safety drum. For this purpose, the safety cable 38 is attached to the governor rope 31 of car C'. It will be apparent that, in the event of overspeeding of car C' from any cause, the governor 36 will trip its rope-gripping jaws 37 to grip the governor rope 31 and apply the safety device S' in the conventional manner.

In order that the governor ropes 17 and 31 may also be utilized to prevent collisions between cars, the governor rope attached to each car passes through between a pair of brackets B or B' and a pair of pivoted jaws A or A' mounted on each other car. Normally, the ropes move freely through the brackets B or B' and the jaws A or A', and the cars may assume various relative positions in their movements up and down the hatchway. Secured to the governor rope 31 of the lower car C', at a predetermined spaced distance above the car, is a small wedge attachment 41 which is adapted to pass freely through the brackets B and to separate the pivoted jaws A on the upper car C when the latter approaches the lower car. A similar wedge attachment 42 is attached to the governor cable 17 below car C.

When the rope 31 carries the wedge attachment 41 between the jaws A, it causes them to be opened and associated contact members 43 to be disengaged. The specific structure of the pivoted jaws is clearly shown in Figs. 2 and 3, from which it may be seen that a biasing spring 44 normally holds the jaws closed and the contact members 43 engaged. A slidably mounted spring-pressed latch 45 engages a detent 46 on the side of one of the jaws A. A stop pin 47 limits the movement of the other jaw, and the spring-pressed latch 45 holds the jaws open and the contact members 43 separated after the passage of the wedge attachment until the device is manually reset.

The disengagement of the contact members 43 interrupts the main control circuit, which

extends therethrough, and thereby deenergizes the hoist motor EM of the upper car C and causes the machine brakes 13, 14 to be applied. This operation must occur only 5 when the cars are moving down. If, when the cars are moving upward, the upper or leading car were suddenly retarded in this manner, a collision would be caused instead of being prevented. Therefore, in order to 10 prevent such operation and render the contact members 43 ineffective to open the control circuit when the cars are moving upwardly, contact members "a" on the "up" relay UR are connected in parallel there- 15 with.

In order to apply further retarding force, in the event that the first operation is not effective, a large stop ball 46 is attached to the governor rope 17 of car C, at such position below the car that it will engage the bracket B' on car C' after the wedge 41 on rope 31 has entered the jaws A on car C. If the opening of the contact members on the jaws A is not effective to check the downward motion of the car C by deenergizing the hoist motor and applying the machine brake, and the car C continues to move downward at a higher velocity than car C' and continues to approach the latter, the stop ball 46 will engage the bracket B' on the car C'. The continued movement of the car then pulls the "minnie ball" 21 from the spring clip 22 on the car C, unreels the safety cable 25 from the safety drum and applies the safety device S to grip the guide rails and retard the downward movement of the car C.

In order to prevent the corresponding stop ball 51 on governor rope 31 from engaging the bracket B on car C and applying the safety device on the lower or leading car C', an electromagnet 52 is provided thereon for moving the bracket to an ineffective position. The electromagnet 52 is connected into the energizing circuit of down relay DR of car C and is, therefore, energized whenever the car is moving downwardly.

The control system of car C' is identical with that shown for car C, and the contact members of its pivoted jaws and the electromagnet of its bracket device have a similar relation to its control circuits, except that the parallel shunting contacts for rendering its pivoted jaws A' ineffective are on the down-direction relay instead of on the up-direction relay, and the electromagnet, associated with bracket device B', is in series with the energizing circuit of the "up" relay instead of in series with the "down" relay, as indicated by the legends on the drawings.

As shown in Figs. 4 and 5, the specific structure of the bracket device comprises a base plate 61 which presents upturned spacing projections 62 and 63 and guide pins 64 and 65 integral therewith. Roller guides 66 and 67 are pivotally mounted on each side of the

base plate 61. A pair of bracket members B rest on the base plate 61 and are held in place in slidable relation thereto by the electromagnet structure 52 which is secured in spaced relation to the base plate by bolts or 70 screws 72. The outer extremity of each bracket member B is of hook formation, and the inner extremity of each is provided with an opening through which a bracket shaft or 75 rod 73 extends in transverse relation to the base plate.

An armature member 74 is pivotally mounted on a shaft 75 which also carries cranks 76 that engage the ends of the bracket shaft 73 by slotted connections. Biasing 80 springs 77 are mounted in compressed relation between the bracket shaft and stop members 78 rising from the base plate 61. The tension of the springs 77 normally urges the bracket members B outwardly and the guide 85 rollers 66 and 67 engage cam surfaces 79 on the sides of the bracket members B to force them together in juxtaposed relation.

When the bracket members are in closed position, the governor ropes and wedge attachments can pass freely through the opening presented by the outer extremities of the bracket members. The stop balls, however, are larger and cannot pass through the contracted bracket members. It is to be noted 90 that the bracket device and the associated governor rope and stop ball are shown in Figs. 4 and 5 on a much smaller scale than is used in representing the pivoted jaws, governor rope and wedge attachment in Figs. 2 95 and 3.

When the electromagnet 52 of the bracket device is energized, the armature 74 and crank members 76 are rotated clockwise, and the bracket B are thereby retracted to the left. 100 As they move to the left, the brackets are separated by the guide pins 65 and 66 and are opened to such an extent that the stop ball 51 can pass freely therebetween.

My invention is best understood, however, 110 when considered with reference to an assumed operation thereof.

Assuming that the cars C and C' are standing at their respective lower terminals, the operator of car C may start his car up by 115 moving the car switch CS counterclockwise. As the switch engages its first contact member, on the right-hand side, its up relay UR is energized.

The circuit by which the relay UR is energized may be traced from the main-line conductor L1, through conductors 91 and 92, thence, by way of contact members 43 on the pivoted jaws A and conductors 102 and 103, to the first contact member 104 of the car 120 switch CS. The circuit continues, through the bridging segment of the switch to its first contact member on the right-hand side, thence, by way of conductor 106, to the winding of relay UR, and, by way of conductors 125 130

107, 108, 109 and 110, to the other line conductor L2.

The relay UR, being energized, pulls up its armature to close its contact members *a*, *b*, *c*, and *d*. Contact members "*a*" complete a shunt circuit around the contact members 43 on the pivoted jaws A by way of conductors 91, 111 and 102 whereby an energizing circuit for relay UR is thereafter maintained independently of the position of the pivoted jaws A. Contact members "*b*" and "*c*" complete an energizing circuit for the independently excited field winding GF of the generator, which may be traced from conductor L1, by way of conductors 91 and 112, through the contact members "*c*" of relay UR, conductors 113 and 114, field winding GF, conductors 115 and 116, contact members "*b*" of relay UR, thence, by way of conductor 117, resistors R1 and R2, and conductor 118, to main-line conductor L2. The field winding GF of the generator G is now energized, and the generator energizes the hoist motor EM to run in the proper direction to raise the car. The contact members "*d*" of relay UR complete a circuit for the brake winding 15, and the brake 13, 14 is now released to permit the car to move freely. The circuit for the brake may be traced from the main-line conductor L1 through conductors 91 and 121, brake winding 15, conductors 122, contact member "*d*" of relay UR and thence, by way of conductors 108, 109 and 110, to main-line conductor L2.

As the car operator continues the movement of the car switch CS in a counter-clockwise direction, a circuit is completed for operating the car at an intermediate speed, which circuit extends from the line conductor L1, by conductors 91 and 92 thence, by way of the contact members 43 on the pivoted jaws A, or by way of a parallel circuit through the contact members "*a*" of relay UR, to conductor 102 and the bridging segment 105 of the car switch, thence through the second right-hand contact, conductor 124, the winding of relay IR and conductors 125, 126, 110, to line conductor L2. The contact members of relay IR will consequently be closed to shunt the resistor R1 from the circuit previously traced for the field winding GF, to thereby cause the car to travel at a higher speed.

To cause the car to travel at full speed, the car switch CS may be moved to its last position in the counter-clockwise direction wherein it causes the energization of the high-speed relay HR through a circuit extending from the line conductor L1 to the bridging segment 105 of the car switch CS, as previously traced, thence, by way of the third and last contact member on the right-hand side of the switch and the conductor 131, to the winding of the relay HR, thence, by way

of conductors 125, 126 and 110, to the other line conductor L2.

The energization of the high-speed relay HR and the closing of its contact members serve to shunt the resistor section R2 from the circuit previously traced for the field winding GF, thereby allowing full line voltage to be applied to the winding GF to cause the car to travel at high speed.

The operator of car C' may start his car up at any time after the car C has departed, and he accomplishes this by moving his car switch CS' counter-clockwise and operating the associated control system in a manner similar to that set forth above with reference to car C. The only difference in the operation of starting car C' upward is apparent from the legends applied to the drawings. Since the electromagnet 132 of the bracket device B' on car C' is connected in series with the up relay, it will be energized to withdraw the bracket members B' to ineffective position. Since the contact members 133 on the pivoted jaws on car C' are shunted by contacts on the associated down relay, they will not be shunted when the car is started up.

When the cars C and C' are moving up the hatchway, each governor rope is constrained to move in accordance with the movements of the car to which each is releasably connected by its "minnie ball" and the spring clip on the car.

Assume now that, for some reason, car C' travels at a higher velocity than car C, or that car C stops and is approached by car C'. The wedge attachment, 42 on the governor rope 17 of car C will pass freely through the brackets B' on car C', and the wedge 41 on the governor rope 31 will pass freely through the brackets B on car C, since the openings therebetween are always large enough to permit the free passage of the wedge members.

As the car C' continues to approach the car C, the wedge attachment members 41 and 42 approach the pivoted jaws A and A' and enter therebetween to open the jaws and separate the contact members associated therewith. The separation of the contact members 43 on jaws A has no effect on the car C, since, as previously set forth, a shunt circuit was completed in parallel therewith through the contact member "*a*" of relay UR. However, the contact members 133 on the pivoted jaws A' on car C' are not shunted, and, when the wedge attachment 42 causes the separation thereof, the control circuit for car C' is opened, its hoist motor is deenergized and the brake is applied.

If the preceding operation is not sufficient to check the upward velocity of car C' and it continues to approach car C, the large stop ball 51 on the governor rope 31 of car C' will approach the bracket B on car C, and, simultaneously, the bracket B' on car C' will ap-

proach the stop ball 46 on the governor rope 17 of car C.

Since the electromagnet of the bracket device B' is energized, the bracket members are separated, and the stop ball 46 passes through freely, and the safety device of car C is not applied. However, the electromagnet of the bracket device B on car C is not energized, and the bracket members B engage the stop ball 51 on the governor rope 31 of car C'. As the car C' thereafter continues to approach car C, the "minnie ball" is pulled away from the spring clip on car C', and the associated safety cable 38 is unreeled to apply the safety and stop the car. Consequently, in the event that the deenergization of the hoist motor and the application of the machine brake fails or is not sufficient to retard car C', the safety device is actuated to grip the guide rails, and the car C' is stopped.

When the cars are moving downwardly, and car C approaches car C', similar operations occur with reference to car C which is then the approaching or following car. The hoist motor of car C is deenergized and the machine brake is applied. If this is not sufficient to retard car C, which continues to approach car C', the safety device S will then be applied, and car C will be stopped.

During this operation, the hoist motor and the brake of car C' will not be deenergized when the wedge 42 enters device A', since the contact members 133 on the pivoted jaws A' of car C' are shunted by contacts on the down relay and are thereby rendered ineffective. The safety device S' on car C' will not be applied, since the bracket members B of car C are held apart by the associated electromagnet 52 which is energized in series with the down-direction relay DR and the stop ball 51 on the governor rope 31 of car C' passes freely between them.

It will be seen that I have provided a multiple-elevator safety system whereby a plurality of elevator cars may be safely operated in the same hatchway. It has been demonstrated that my system operates to prevent collisions between the cars by applying a succession of steps of retardation to the approaching car only.

Although I have shown and described a certain specific embodiment of my invention, I am fully aware that many modifications thereof are possible. My invention, therefore, is not to be restricted except insofar as is necessitated by the prior art and by the spirit of the appended claims.

I claim as my invention:

1. In combination, a pair of elevator cars operable in a single hatchway, a control system comprising a hoist motor and machine brake for each car, a safety braking device carried by each car, means actuated by the proximate approach of either car toward the other car for deenergizing the hoist motor

and applying the machine brake associated with the approaching car only, and means operable for applying the safety device on the approaching car only, if it thereafter continues to approach the other car. 70

2. In a system for operating a plurality of elevator cars in the same hatchway, a plurality of cars, a safety grip for each car, speed-responsive means for each car for actuating the safety grip for the associated car, and means operable in accordance with the reduction of the distance between the cars for applying the safety grip on the approaching car only, irrespective of its speed. 75

3. In combination, a pair of elevator cars operable in a single hatchway, a safety braking device carried by each car, means for applying the safety device on the lower car when it approaches within a predetermined distance of the upper car, means for applying the safety braking device on the upper car when it approaches within a predetermined distance of the lower car, means for rendering said first means ineffective when the cars are traveling down, and means for rendering said second means ineffective when the cars are traveling up. 80 85 90

4. In combination, a pair of elevator cars operable in a single hatchway comprising an upper car and a lower car, a safety braking device carried by each car, a safety actuating rope releasably secured to each car and passing around sheaves at the top and the bottom of the hatchway, a pair of movable brackets so positioned on each car that the rope associated with the other car normally passes freely therebetween, a stop ball secured to the rope of the lower car at such a position thereon that it will strike the bracket of the upper car when the lower car approaches within a predetermined distance thereof to thereby set the safety device on the lower car, means on the upper car for moving the associated stop brackets to ineffective position when said car is moving down, and means on the lower car for moving the stop brackets to ineffective position when said car is moving up, whereby the approach of one car toward the other will not actuate the safety device on the leading car. 95 100 105 110 115

5. In combination, a pair of elevator cars operable in a single hatchway comprising an upper car and a lower car, a control system for each car comprising a hoist motor and a machine brake, a rope secured to each car and passing around sheaves at the top and bottom of the hatchway, a pair of movable jaws mounted on each car and so positioned that the rope from the other car normally passes freely therewith, a pair of normally closed contact members associated with each pair of jaws whereby they are actuatable to circuit interrupting position when the jaws are moved from their normal rela- 120 125 130

tive position, means for connecting each pair of contact members into the main control circuit of the associated car, a wedge attachment secured to the rope of the lower car at 5 such position thereon that it will engage and open the jaws of the upper car when the upper car approaches within a predetermined distance of the lower car to thereby deenergize the hoist motor and apply the machine 10 brake associated therewith, means for rendering said contact members on the upper car ineffective when the car is traveling up, a wedge attachment secured to the rope of the upper car at such a position thereon that it 15 will engage and open the jaws of the lower car when the lower car approaches within a predetermined distance of the upper car to thereby deenergize the hoist motor and apply the machine brake associated therewith, and means for rendering the contact members on the lower car ineffective when the car is traveling down.

6. In combination, a pair of elevator cars operable in a single hatchway comprising 25 an upper car and a lower car, a safety braking device carried by each car, a governor rope releasably secured to each car, an overspeed governor driven by each governor rope at speeds corresponding to the speed of the 30 associated car, rope-gripping jaws actuated by each governor to grip the governor rope and set the safety device on the associated car when it over-speeds, a pair of movable brackets on each car so positioned that the 35 governor rope of the other car normally passes freely therebetween, a stop ball secured to the governor rope of the lower car at such a position thereon that it will strike the bracket on the upper car if the lower 40 car approaches within a predetermined distance thereof to thereby set the safety device on the lower car irrespective of its speed, a stop ball secured to the governor rope of the upper car at such position thereon that 45 it will strike the bracket on the lower car if the upper car approaches within a predetermined distance thereof to thereby set the safety device on the upper car, irrespective of its speed, means on the upper car for moving 50 the associated stop brackets to ineffective position when said car is moving down, and means on the lower car for moving the stop brackets to ineffective position when said car is moving up, whereby the approach 55 of one car toward the other will only actuate the safety device on the approaching car and not on the leading car.

In testimony whereof, I have hereunto subscribed my name this 23rd day of December, 60 1930.

HENRY D. JAMES.
